PORTABLE ILLUMINABLE MIRROR

Ronald D. Goldman, Northridge, and Theodore J. Slavin, Tarzana, Calif., assignors to Tedron Industries, Inc., a corporation of California

Filed Aug. 12, 1968, Ser. No. 13,105

Term of patent 14 years

Int. Cl. D3—99

U.S. Cl. D86—10

FIG. 1 is a front perspective view of a portable illuminable mirror showing our new design;

FIG. 2 is a front elevational view thereof;

FIG. 3 is a side elevational view; and

FIG. 4 is a back elevational view.

We claim:

The ornamental design for a portable illuminable mirror, as shown.
